UNITED STATES PATENT OFFICE.

OSWALD S. PULLIAM, OF PITTSBURG, PENNSYLVANIA, ASSIGNOR TO PITTSBURGH EQUIPMENT COMPANY, OF PITTSBURG, PENNSYLVANIA, A CORPORATION OF PENNSYLVANIA.

SIDE-FRAME CONSTRUCTION.

No. 852,079.

Specification of Letters Patent.

Patented April 30, 1907.

Application filed January 29, 1907. Serial No. 354,678.

To all whom it may concern:

Be it known that I, OSWALD S. PULLIAM, of Pittsburgh, in the county of Allegheny and State of Pennsylvania, have invented certain new and useful Improvements in Side-Frame Construction, of which the following is a specification.

The prime object of my invention is to provide a new and improved side-frame construction for car-trucks and to this end the present invention consists, of a new and improved side-frame construction for car-trucks, in the novel features of construction, and in the combination of parts all as fully hereinafter described and claimed.

In the accompanying drawing which illustrates an application of my invention, Figure 1, is a side elevational view of my side-frame construction; Fig. 2, a similar view of the side-frame without the bolster, bolster-springs, etc.; Fig. 3, a detail sectional view taken on line 3—3 of Fig. 1; Fig. 4, a sectional view taken on line 4—4 of Fig. 1; and Fig. 5, a perspective view of a removable bolster-guide.

Referring to the drawing, 1 designates a side-frame proper preferably made of cast metal and as an integral structure. The frame is formed with a centrally disposed bolster receiving opening 2.

The form of bolster 3, as illustrated, is provided with column-guides 4 and is adapted to have its ends inserted into opening 2.

The lower portion of opening 2, is wider than the upper portion and the width of the lower portion should be at least as great as the width of the bolster measured over its column-guides 4. The purpose of this construction is to enable the bolster-ends to be readily inserted into the said enlarged portion of the opening. The width of the upper portion of the opening is less than the width of the bolster measured over its column-guides and this portion is bounded by a flange 5 extending along the top and sides of the smaller portion of the opening. The

side flanges 5 serve as bolster-guides for the bolster when the parts are assembled.

6 designates removable bolster-guides preferably of the form shown, that is, comprising a forked engaging portion 7, a flat bearing face 8 and vertical edges 9 all as particularly shown by Fig. 5. When the removable bolster-guides are assembled with the other parts, the forked portion of each guide straddles the web 10 of the side-frame proper and the vertical edges 9 form a continuation of the bolster-guides or side-flanges 5 and are in contact with the column-guides 4 formed on the bolster.

11 designates the usual bolster-springs employed in constructions of this nature, their upper ends being in contact with the bolster and their lower ends surrounding studs 12 of a plate 13.

What I claim is:

1. In a truck side-frame construction, the combination with a bolster having column-guides, a side-frame proper having a bolster receiving opening, fixed bolster-guides 70 formed on the side-frame adjacent to the sides of the opening and removable bolster-guides below the fixed bolster-guides and forming a continuation thereof.

2. In a truck side-frame construction, the combination with a bolster having column-guides, a side-frame proper provided with a bolster receiving opening having its lower portion at least as wide as the bolster measured over its column-guides and the upper portion of less width than the bolster measured over its column-guides, bolster-guides formed on the side-frame adjacent to the sides of the smaller portion of the opening, and removable bolster-guides below the fixed 85 bolster-guides.

In testimony whereof I affix my signature in presence of two witnesses.

OSWALD S. PULLIAM.

Witnesses:

MARGARET HUGHES,
W. G. DOOLITTLE.
